UNITED STATES PATENT OFFICE.

GEORGE W. BROWN, OF GALESBURG, ILLINOIS.

CORN-PLANTER CHECK-ROWER.

SPECIFICATION forming part of Letters Patent No. 278,500, dated May 29, 1883.

Application filed January 22, 1883. (Model.)

To all whom it may concern:

Be it known that I, GEORGE W. BROWN, a citizen of the United States, residing at Galesburg, in the county of Knox and State of Illinois, have invented certain new and useful Improvements in Corn-Planter Check-Rowers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

In the use of corn-planter check-rowers of that class in which the actuating mechanism is a tappet-wire stretched across the field and adapted to act on a forked lever or levers, and especially in that class thereof in which the forked lever swings in a horizontal plane, it is found that the tappets will sometimes escape from the forked lever before said lever has made its full throw and before it has given a full throw to the seed-slides of the planter; and the object of this invention is to provide means for insuring the contact of the tappets with the forked lever until said lever has made a full throw, and then permitting the tappets to escape freely from said lever; and to this end this invention consists, mainly, in a latch hinged to the forked lever and adapted to retain the tappets in contact with the forked lever and release the tappets therefrom at proper intervals.

The invention further consists in constructions and combinations hereinafter described.

In the accompanying drawings, which illustrate my invention, Figure 1 is a top plan. Fig. 2 is a side elevation; Fig. 3, a sectional elevation in line $x-x$ in Fig. 1, but the forked lever at forward end of its throw.

The drawings show my improvement applied to one of that class of check-rowers in which a bar, A, located transversely on the planter, has a similar set of check-row devices secured to each of its ends, only one set of which is shown.

B is a head secured transversely to and on the bar A, and provided at its front end with guide-pulleys C, and at its rear end with guide-pulleys D, for the tappet-wire E.

F is the forked lever, elbow-shaped and journaled at f. The outer end of the lever F is

forked, and its inner end is hinged or journaled to a rod, G, which extends to the seed-slides of the planter. (Not shown.)

H is a stop for the forked lever.

I is a spring for returning the forked lever after it has been swung rearward by the action of the tappets e of the wire E.

The foregoing parts described by letter are parts of an ordinary check-rower, and need not be described more fully herein, as they may be of ordinary construction, except as hereinafter described.

M is a latch hinged at m, near one of its ends, to the forked lever F, so that it may swing in a vertical plane. Near its outer end the latch is curved upwardly to form a shoulder, m', and thence outwardly it slopes downwardly on its upper side to form a face, m'', for facilitating removing and replacing the wire in the fork. When the latch M is in its closed position, as shown at Fig. 3, its rear end or heel, m''', rests on a lug, f', which projects from the side of the forked lever, and the point m' of the latch is so near the upper limb of the forked lever as to retain a tappet e in the fork, but not so near as to prevent inserting the wire of the tappet-wire laterally therein over the face m'' and withdrawing it therefrom in same manner, as is necessary at the ends of the rows being planted. The upper face of the head B is straight from b to b', and from b' is cut away in a slope, b'', rearward to form a face, b''', in a lower plane than b b'. During all the forward part of the throw of the forked lever E the latch M is held up in its closed position, as shown at Fig. 3, by the faces b b'; but when it reaches the slope b'' in its rearward throw the heavier outer end of the latch will drop by its own gravity, as shown at Fig. 2. As the spring returns the forked lever forward, the sloping face b'' will raise the latch again to the slide-way b b'.

At Fig. 1 the forked lever is shown as having made a partial throw rearward by the action of one of the tappets e, and at same figure the wire E, curved outwardly, shows the tendency of the wire to escape from the forked lever, which is prevented by the tappet e coming in contact with the shoulder m' of the latch. When the forked lever completes its throw the latch will lower on the incline b'', as already

described, and permit the tappet to escape from the forked lever, which will then be returned forward by the spring. As shown, the latch is adapted to act on a forked lever which swings in a horizontal plane; but by placing a spring between the heel of the latch and the lug f' it will act on a forked lever which swings in a vertical plane.

Having thus described my invention, what I claim as new, and desire to secure by Letters Patent, is—

1. In a corn-planter check-rower, in combination with a swinging forked lever and a tappet-wire, a latch hinged to the forked lever and adapted to retain the tappets in contact with the forked lever until it completes its throw, substantially as and for the purpose specified.

2. In combination with the forked lever and tappet-wire, the latch M, hinged to the forked lever, and provided with a shoulder, m' , and face m'' , substantially as and for the purpose specified.

3. In combination with the forked lever and tappet-wire, the gravitating latch, adapted to

operate substantially as and for the purpose 25 specified.

4. In combination with the forked lever and latch hinged thereto, the head B, having a face, $b\ b'$, with a depression at its rear end, whereby it may retain the latch to hold the tappets during part of its throw and allow it to fall to release them at the end of each throw, substantially as and for the purpose specified.

5. In combination with the swinging forked lever and tappet-wire, the latch M, with a heel 35 end, m'''' , and the lug f' , with which it coats, substantially as and for the purpose specified.

6. In combination with the tappet-wire and swinging forked lever having a lug, f' , the latch M, constructed substantially as described, 40 for the purpose specified.

In testimony whereof I affix my signature in presence of two witnesses.

GEORGE W. BROWN.
